UNITED STATES PATENT OFFICE.

ADOLPH Y. S. ALBUM, OF CHICAGO, ILLINOIS.

HAIRPIN.

1,390,856.

Specification of Letters Patent. Patented Sept. 13, 1921.

Application filed December 29, 1920. Serial No. 433,818.

To all whom it may concern:

Be it known that I, ADOLPH Y. S. ALBUM, a citizen of the United States, residing at Chicago, in the county of Cook and State of Illinois, have invented a certain new and useful Improvement in Hairpins, of which the following is a full, clear, concise, and exact description, reference being had to the accompanying drawings, forming a part of this specification.

My invention relates to hair pins.

The principal object of the invention is to provide a hair pin which will be retained in position in the hair sufficiently to prevent its falling out or being accidentally knocked out, but at the same time to permit the withdrawal of the pin from the hair by hand whenever desired.

The principal features of the invention reside in a double or interlocking means on the pin for intertwining between strands of hair embraced by the pin and those exterior of the pin, these means being provided by catch pockets opposed to the withdrawing movement of the pin from the hair.

The invention also resides in the sundry details of construction and in the formation of the various parts described in detail in the following specification.

In the accompanying drawing the figure shows a hair pin embodying my invention.

Referring to the drawing I show a hair pin A, having two sides or tines 1 and 2, each provided with the usual irregularities 3 and 4. One of the sides, as for example the side 2, is also provided at a point near the head X of the pin with a hair engaging device, which is preferably in the form of a bend or kink in the wire or rod material forming the hair-pin and provides a lateral inwardly projecting open-loop 5 lying in the same plane of tines 1 and 2. The loop 5 extends in close proximity to the tine 1 so as to contract the space between the tines at this point, thereby providing a constricted

passage Z therebetween and an enlarged hair-locking pocket Y between it and the end X of the pin. The open-loop 5 also provides a notch 5^a opening outwardly from the exterior of the pin to receive and pocket the hair lying exteriorly of the pin. The portion 5^b of the loop is extended from the

tine 2 abruptly at an inclination toward the open end of the pin, and the portion 5^c thereof is not so abruptly extended from the tine but extends more on a rounding-curve thereby providing the notch 5^a with an entrance somewhat inclined to the general direction or length of the tine 2 and directed toward the head of the pin. This particular formation of the portions 5^b and 5^c of the loop provides concaved catch shoulders or surfaces 5^d and 5^e extending at substantially right angles to the axis of the pin, thus forming pockets which insure the retention of the hair therein when the latter is expanded after being compressed through the restricted passage Z and the restricted entrance of the notch 5^a.

The loop 5 is preferably, but necessarily, disposed adjacent the close end of the head X of the pin for two reasons, among others, namely; first, in order to coöperate with closed end or head X, to provide the catch or retaining pocket Y, and, second, because of the accessibility of the head X, when the pin is in the hair, to extricate the hair engaging in the pocket Y and the notch 5^a.

Thus it will be seen that the pin of the present invention is provided with double lock or catch means, which when the pin is secured in the hair, interlock themselves between the strands of a lock or hank of hair in such a manner as to intertwine between the hair embraced by the pin at its head and the adjacent strands of hair exterior of the pin, thereby doubly insuring against slipping out or accidental withdrawal.

When it is desired to remove the pin the head X is taken hold of and the pin moved slightly to one side to liberate the hair engaging the notch 5^a, and then pull the pin forcing the hair in the pocket Y through the passage Z.

It will be understood that changes and modifications may be made without departing from the spirit of the invention.

What I claim is:

1. A hairpin comprising a pair of tines connected together at one of their ends, means on one of said tines for engaging hair embraced by the pin, and other means on one of said tines for engaging hair lying exterior of the pin, both of said means having

catch-surfaces thereon extending at least 90 degrees relative to the axis of the pin and from the open end thereof, whereby said means directly oppose the withdrawing movement of the pin from the hair and co-operate to lock the pin in the hair.

2. A hairpin comprising a pair of tines connected together at one of their ends, a lateral inward projection on one of the tines 10 and lying substantially in the plane of the tines for engaging hair embraced by said pin, means on one of said tines for engaging hair lying exterior of the pin, said means and said projection each having catch-surfaces 15 thereon extending at least 90 degrees relative to the axis of the pin and from the open end thereof, whereby said means directly oppose the withdrawing movement of the pin from the hair and co-operate to lock 20 the pin in the hair.

3. A hairpin comprising a pair of tines connected together at one of their ends, a lateral inward loop formed on one of the tines, lying between the tines and in the 25 plane thereof, said loop being spaced from the opposite tine and having a surface thereon opposite the closed end of the pin extending at least 90 degrees relative to the axis of the pin and from the open end thereof, 30 whereby said means directly oppose the withdrawing movement of the pin.

4. A hairpin comprising a pair of tines connected together at one of their ends, one of said tines being bent to form a loop projecting inwardly between the tines, said loop being spaced from the other tine and forming a pocket between it and the closed end 35 of the pin, the surface of the loop opposite the closed end of the pin being concaved to engage with the hair lying in said pocket and oppose the withdrawing movement of the pin from the hair.

5. A hairpin comprising a pair of tines connected together at one of their ends, one of said tines being bent to form a loop projecting inwardly between the tines, said loop restricting the space between said tines at the point opposite the loop and forming a pocket between the loop and the closed end 50 of the pin, said loop also providing a notch opening outwardly of the pin to receive the hair lying exterior of the pin, said notch having a restricted entrance.

6. A hairpin comprising a pair of tines connected together at one of their ends, one of said tines being bent to form a loop projecting inwardly between the tines, said loop restricting the space between said tines, at the point opposite the loop and forming a 60 pocket between the loop and the closed end of the pin, said loop providing a notch opening outwardly of the pin to receive the hair lying exterior of the pin, said loop and notch having catch-surfaces thereon extending at least 90 degrees relative to the axis

of the pin and from the open end of the pin, whereby said means directly oppose to the withdrawing movement of the pin from the hair and co-operate to lock the pin in the hair.

7. A hairpin comprising a pair of tines connected together at one of their ends, one of said tines being bent adjacent the closed end of the pin to form an open-loop substantially circular, said loop projecting inwardly between the tines and spaced from said other tine to provide a pocket between the loop and the closed end of the pin for receiving hair embraced by the pin, said loop providing a notch between the open 80 ends thereof and opening exteriorly of the pin to receive hair lying outside of the pin.

8. A hairpin comprising a pair of tines connected together at one of their ends, one of said tines being bent to form an open-loop, said loop projecting inwardly between the tines and spaced from said other tine to provide a pocket between the loop and the closed end of the pin, said loop providing a notch opening exteriorly of the pin and 90 having an entrance extending in the general direction of said tine and directed toward the closed end of the pin.

9. A hairpin comprising a pair of tines connected together at one of their ends, one of said tines being bent adjacent the closed end of the pin to form an open-loop, said loop projecting inwardly between the tines and spaced from said other tine to provide a pocket between the loop and the closed end 100 of the pin for receiving hair embraced by the pin, said open-loop also providing a notch between the ends thereof and opening exteriorly of the pin to receive hair lying outside of the pin, said notch having an entrance extending in the general direction of said tine and directed toward the closed end of the pin, the surface of the loop opposite the closed end of the pin and the surface of said notch nearest the open end of the pin being concaved for the purposes set forth.

10. A hairpin comprising a pair of tines connected together at one of their ends, one of said tines being formed to provide an open-loop, the end of the loop nearest the free end of the tine being abruptly bent at an acute angle and the end of the loop nearest the closed end of the pin being curved, whereby a notch is produced having a restricted entrance extending in a general direction of the tine toward the closed end of the pin.

11. A hairpin comprising a pair of tines connected together at one of their ends, one of said tines being formed to provide an open-loop, the end of the loop nearest the free end of the tines being abruptly bent at an acute angle and the end of the loop nearest the closed end of the pin being 125

curved, whereby a notch is produced having a restricted entrance extending in a general direction of the tine and toward the closed end of the pin, said loop projecting inwardly between the tines of the pin and spaced from the opposite tine to provide a

hair-receiving pocket between the loop and the closed end of the pin for the purposes set forth.

In witness whereof I hereunto subscribe my name this 21st day of December, A. D. 1920.

ADOLPH Y. S. ALBUM.
